UNITED STATES PATENT OFFICE.

ALFREDO SCOTTI, OF WHITTIER, CALIFORNIA.

TRACTION DEVICE.

1,416,237.

Specification of Letters Patent. Patented May 16, 1922.

Application filed April 6, 1921. Serial No. 453,897.

To all whom it may concern:

Be it known that I, ALFREDO SCOTTI, a citizen of the United States, residing at Whittier, in the county of Los Angeles and State of California, have invented a new and useful Traction Device, of which the following is a specification.

My invention relates to traction wheels such as are used on tractors and the like for hauling farm implements, being more particularly a wheel which is equipped with devices to render the employment of such wheels efficient in sandy soil.

In common forms of traction wheels, when used in sandy soils, the tendency of the flights on the wheel is to dig out the soil and partially bury the wheel as the sand offers little resistance to the action of the flights.

It is the principal object of my invention to produce a wheel provided with stationary flights and movable packers mounted on the wheel which coact with the flights to pack the soil or sand behind the flights, thereby offering sufficient resistance to the flights to prevent the digging action of the flights which takes place with wheels constructed in the ordinary manner.

Another object of my invention is to produce a wheel of the class described of simple form which may be quickly adjusted for road travel so that the wheel presents a flat face or tread for riding upon the surface of the road.

Other objects and advantages will appear hereinafter from the following description and drawings.

Referring to the drawings, which are for illustrative purposes only,

Fig. 1 is a side elevation, partly in section, of a traction wheel embodying a form of my invention, the adjusting device being removed.

Fig. 2 is a plan view of the wheel shown in Fig. 1.

Fig. 3 is a sectional view on line 3—3, Fig. 1.

Fig. 4 is a side elevation of a portion of the wheel shown in Fig. 1, the adjusting device being shown thereon.

Fig. 5 is a sectional view on line 5—5, Fig. 4.

Fig. 6 is a side view, partly in section, of the wheel shown in Fig. 1 partly disassembled.

Fig. 7 is a sectional view on line 7—7, Fig. 6.

Fig. 8 is a side view, partly in section, of a modified form of the wheel.

Fig. 9 is an inverted plan view of a part 60 of the wheel shown in Fig. 8.

Fig. 10 is a side elevation, partly in section, of a part of a wheel showing a still further modification of the wheel.

Referring more particularly to the form 65 of wheel shown in Figs. 1 to 6 inclusive, 11 designates the hub of the wheel from which extends outwardly a series of flat spokes 12, such spokes being jointed at their outer ends by two circular ribs 13, there being one such 70 rib on each side of the spokes. The ribs 13 are connected intermediate of the spokes by means of flat webs 15, such webs 15 and the spokes being used for the purpose of mounting flights 16 thereon. Each flight 16 consists of a flat plate secured to the spokes and webs respectively by means of bolts 17, such flights extending outwardly from the wheel beyond the periphery of the ribs 13. Each flight 16 is provided with a rearwardly extending flange 18 at each side thereof, the inner end of such flange resting upon the outer edge of the ribs 13 forming bracing 80 means for the flight. Each flange 18 is perforated, as shown at 20, to receive a bolt 21 85 upon which is pivotally mounted a swinging presser foot 22. Each presser foot 22 consists of a curved tread plate 24 of greater width than the ribs 13 and is provided with inwardly extending flanges 25 which 90 embrace the flanges 18 on the flights 16. The bolts 21, heretofore referred to, extend through the flanges on the presser foot and through the flanges 18 of the flights, such bolts being secured by means of suitable 95 nuts 26 thereon.

It is to be noted that the curved outer face or tread of the plates conforms to a circle formed by such plates when the plates are in their extended position, as indicated 100 at 28 in Fig. 1, the outward swinging movement of such plates being limited by the inner face of the plates coming into contact with the outer edge of the flights 16.

The wheel is provided with a flat tread 105 which is placed on one side of the wheel, such tread consisting of a ring 30 having a flange 31 which is secured by means of suitable bolts 32 to one of the ribs 13 of the wheel, as clearly shown in Fig. 3.

The wheel, when used, operates in the following manner:

Assuming the wheel to be revolving in the direction of the arrow shown in Fig. 1, the 5 lowermost flights enter the ground, indicated at 35, as shown, the sand or dirt between the flights being pressed upon and held in compact condition behind the flights by the presser feet 22. This action of the presser 10 feet between the flights tamps or packs the dirt, as indicated at 36, behind the flights thereby providing resistance to the action of the flights resulting in sufficient traction to permit propulsion of the vehicle in such soil. 15 As the flights leave the ground, the presser feet are permitted to swing freely and assume the positions indicated in Fig. 1 while the wheel is making its revolutions.

When it is desired to move the vehicle 20 over a roadway, the wheel is adjusted so that the surface of the roadway is not injured. This is done by means of an adjusting device which consists of a circular plate 40 provided with a series of slots 41 through which 25 extend bolts 42 secured in one of the ribs 13, the plate 40 being held in desired position on the rib by means of nuts 43 threaded on the bolts 42. The plate 40 is provided with radially disposed arms 44 which extend outwardly from the plate 40, the outer ends of the arms being rounded and engaging under the tread portion of the feet 22, as shown in Figs. 4 and 5.

When the wheel is being used in the orchard, the plate 40 is adjusted to the full line position shown in Fig. 4, in which position the arms 44 extend over the ends of the bolts 21 preventing dislodgment of such bolts, in which position a free movement of 40 the presser feet is allowed. By moving the plate 40 so that the arms assume the dotted line position shown in Fig. 4, such arms engage under the tread of the presser feet, holding such feet in dotted line position, and 45 form a substantially continuous tread, as shown in dotted lines in such figure.

Figs. 6 and 7 show the wheel with the presser feet removed, in which form the wheel is partly attached for use in heavy soil.

50 In the form shown in Figs. 8 and 9, the movable presser feet are eliminated in which case the flat spokes, designated at 60, extend beyond the ribs 61, the outer ends 62 of such spokes forming flights. The webs, indicated at 63, are also extended outwardly, as indicated at 64, forming flights. The presser feet in this form are stationary and consist of plates 65 which extend from the bottom of one flight angularly to the top of the next flight. The action of this form of wheel is of the same nature as that disclosed in connection with Figs. 1 to 6 inclusive, that is, the plates 65 pack the soil behind the flights, the soil in such packed condition offering the necessary resistance to the flights. While I

have shown a wheel in Figs. 8 and 9 made as a single casting, it is understood that the parts of the wheel may be made separately and secured together in any of the well known common practices in making wheel 70 devices.

In the form shown in Fig. 10, the wheel is substantially the same construction as that disclosed in connection with Figs. 1 to 6 inclusive, with the exception that the flanges 75 formed on the flights extend both forwardly and rearwardly as indicated at 70 and 71, the inner ends of such flange engaging the outer edge of the ribs and bracing the flights on such ribs at both sides instead of on one 80 side as shown in the other figures.

While I have shown the wheel constructed with eight spokes and webs connecting the ribs intermediate the spokes, it is to be understood that I may increase or decrease the 85 number of spokes and that the webs may be eliminated without departing from the spirit of my invention.

I claim as my invention:

1. A traction device comprising a wheel 90 consisting of a hub, spokes extending radially from said hub, circular ribs connecting the outer ends of said spokes, webs connecting said ribs between said spokes and flight members secured to said spokes and said 95 webs.

2. A traction device comprising a wheel 100 consisting of a hub, spokes extending radially from said hub, a circular rib on each side of said spokes connecting the outer ends 100 of said spokes, and a plurality of flight members extending outwardly beyond said ribs, and a presser foot pivotally mounted on the outer end of each flight member.

3. A traction device comprising a wheel 105 consisting of a hub, spokes extending radially from said hub, flight members secured to the outer end of said spokes extending outwardly therefrom, a circular rib on each side of said spokes connecting the outer ends 110 of the spokes, and packing means between said flight members extending from the outer end of one flight member to the base of the next flight member.

4. A traction device comprising a wheel 115 consisting of a hub, spokes extending radially from said hub, flight members secured to the outer end of said spokes extending outwardly therefrom, a circular rib on each side of said spokes connecting the outer ends of 120 the spokes, and a presser foot pivotally mounted on each flight member.

5. A traction device comprising a wheel 125 consisting of a hub, spokes extending radially from said hub, a circular rib on each side of said spokes connecting the outer ends of said spokes, a flight mounted on the outer end of each spoke, flanges on said flights engaging said ribs, and a presser foot pivotally connected to each flight.

6. A traction device comprising a wheel consisting of a hub, spokes extending radially from said hub, a circular rib on each side of said spokes connecting the outer ends 5 of said spokes, a flight mounted on the outer end of each spoke, flanges on said flights engaging said ribs, and a presser foot for each flight, each presser foot consisting of a curved plate, flanges on said plate and a 10 bolt extending through the flanges on the flight and presser foot.
7. A traction device comprising a wheel consisting of a hub, spokes extending radially from said hub, a circular rib on each 15 side of said spokes connecting the outer ends of said spokes, a flight mounted on the outer end of each spoke, flanges on said flights engaging said ribs, a presser foot pivotally connected to each flight and means for holding 20 the presser foot in extended position.
8. A traction device comprising a wheel consisting of a hub, spokes extending radially from said hub, a circular rib on each side of said spokes connecting the outer ends 25 of said spokes, a flight mounted on the outer end of each spoke, flanges on said flights engaging said ribs, a presser foot pivotally connected to each flight, and means for forming 30 a tread of said presser feet.
9. A traction device comprising a wheel, a series of flights extending outwardly from said wheel, a series of presser feet pivotally mounted on said flights, and means for holding 35 said presser feet in extended position to form a tread of said presser feet beyond said flights.
10. A traction device comprising a wheel, a series of flights extending outwardly from
- said wheel, a series of presser feet pivotally mounted on said flights, and means for holding 40 said presser feet in extended position to form a tread of said presser feet beyond said flights, said holding means consisting of a circular member mounted on said wheel arranged to engage said presser feet. 45
11. A traction device comprising a wheel consisting of a hub, spokes extending radially from said hub, a circular rib on each side of said spokes connecting the outer ends 50 of said spokes, a series of flights extending outwardly beyond said ribs, a presser foot pivotally mounted on each flight, a circular member arranged to engage said feet to hold said feet in extended position and form a tread for the wheel. 55
12. A traction device comprising a wheel consisting of a hub, spokes terminating at their outer end in flat webs, a circular rib on each side of said spokes connecting the outer end of said spokes, and a flight member extending outwardly from each web consisting 60 of a flat radially disposed plate.
13. A traction device comprising a wheel consisting of a hub, spokes terminating at their outer ends in flat webs, a circular rib 65 on each side of said spokes connecting the outer end of said spokes, flight members secured to the outer end of said spokes and packing means between said flight members extending from the outer end of one flight 70 member to the base of the next flight member.

In testimony whereof, I have hereunto set my hand at Los Angeles, California, this 1st day of April, 1921.

ALFREDO SCOTTI.
